Primary Examiner—A. Hugo Word*Assistant Examiner*—Doris V. Coles*Attorney, Agent, or Firm*—Benesch, Friedlander, Coplan & Aronoff[57] CLAIM

The ornamental design for a golf club organizer, as shown and described.

DESCRIPTION

FIG. 1 is a perspective view of a golf club organizer showing my new design;

FIG. 2 is a front elevational view thereof;

FIG. 3 is a rear elevational view thereof;

FIG. 4 is an elevational view of the right side thereof;

FIG. 5 is an elevational view of the left side thereof;

FIG. 6 is a top plan view thereof; and,

FIG. 7 is a bottom plan view thereof.

The broken line showing of the remainder of a golf bag in FIG. 1 is for illustrative purposes only and forms no part of the claimed design.
